UNITED STATES PATENT OFFICE.

ANNIE L. CHUBB, OF OAKLAND, CALIFORNIA.

CLOTHES-HANGER HOLDER.

Application filed February 19, 1927. Serial No. 169,522.

My invention relates to clothes-hanger holders, and it refers especially to such holders as are adapted for use in clothes closets or cloak rooms, for instance, in club houses, 5 where frequently a crowded condition of the hanging garments prevails.

In order to retain a desired number of clothes hangers on each holder, it is in such places often desirable to use hangers that have 10 eyes thereon instead of the customary hooks, and for such hangers, it is common to provide holders in the form of straight rods, which are fastened at their ends in suitable supports, so that, as long as the holders are securely 15 fastened at both ends, the hangers cannot be easily removed from the holders and cannot be easily lost. The use of such holders, or 20 holders of any other construction heretofore known, in connection with the aforementioned hangers, has the disadvantage, however, that the holders cannot be swung out of 25 the way when it is so desired, and, if the holders are removed from their fastening the hangers are liable to slide off and, consequent- ly, to be lost.

It is one object of my invention to construct a clothes-hanger holder, which is not only adapted for use in connection with the ordinary hangers having hooks thereon, but is 30 adapted to be threaded thru the eyes of the first mentioned hangers for attaching the hangers to the holders, and to be threaded thru an eye member secured to a suitable support, and to engage a hook member on the 35 support in order to attach the holders thereto for holding hangers in a virtually horizontal alignment with one another on the holder.

A further object of the invention is to provide such a holder with means for preventing 40 the hangers from sliding off the holder or for preventing the holder from becoming disengaged from the eye member, whether the holder engages the hook in the support or is disengaged therefrom, and also for making 45 it possible to swing the attached holder out of the way when the holder is not in use.

With the above mentioned objects and other 50 objects in view, the invention consists in the novel construction and combination of parts, hereinafter described, illustrated in the accompanying drawings, and set forth in the appended claims, it being understood that various changes in the form, proportion, size, and minor details of construction within the 55 scope of the claims may be resorted to without departing from the spirit, or without sacrific-

ing any of the advantages of, the invention. In the drawings:

Figure 1 is a side elevation of a clothes-hanger holder, constructed according to my 60 invention and holding thereon a number of clothes hangers in a virtually horizontal alignment, the view showing also a portion of a wall or other vertical supporting member and a horizontal support secured thereto, 65 which carries an eye member and a hook for attaching the holders to the support;

Figure 2 is a sectional elevation along the line 2—2 in Figure 1; and

Figure 3 is a similar elevation along the 70 line 3—3 in Figure 1.

The clothes-hanger holder of my invention is indicated in the drawing as a whole by the numeral 1. It comprises a rod, which is provided with virtually straight and parallel 75 end portions 2 and 3, a virtually straight, intermediate portion 4 extending virtually parallel with the end portions, bends 5 and 6 joining the intermediate portion to the respective end portions so that the end portion 3 extends 80 between the intermediate portion 4 and the end portion 2 and adjacent to the latter, and a terminal bend 7 formed on the end portion 3 adjacent to the bend 5, and the holder is preferably so constructed that all of its parts 85 are virtually in the same plane, as shown in Figures 2 and 3.

In Figure 2 is shown a clothes hanger 8 provided with an eye 9 by which it is attachable to a support. Hangers of this kind are 90 attached to the holder 1 by threading the straight end portion 2 of the holder thru the eye 9 of each hanger until the eye passes the terminal bend 7 on the other straight end portion 3 and is free to slide down upon the intermediate portion 4. The holder may be 95 attached to any suitable support 10 so as to retain the hangers in the customary horizontal alignment with one another. Such a support may be a shelf, which is shown at 11 in Figure 1 as hinged to a wall or other vertical supporting member 12. Into this shelf are 100 screwed an eye 13 and a hook 14, and the eye and the hook are so spaced from each other as to be adapted to support the holder at the junction of the bends 5, 6, and 7 with the respective straight end portions 2 and 3.

In order to attach the holder to the support 10, the straight end portion 2 is threaded 110 thru the eye 13 until the eye passes the bend 7, so that the holder cannot accidentally become disengaged from the eye and that, if it

is desired to swing the holder out of the way, the holder may be allowed to assume a vertical position and, in such a position, may be supported at one end on the eye by the bend 5. 5 When it is desired to support the hangers in their horizontal positions, the holder is swung into engagement with the hook 14 in such a manner that one end of the holder, with the straight portion 3 at the bend 7, rests in the 10 eye 13, and the other end of the holder, with the straight portion 3 at the bend 6, rests in the hook 14. While the hangers 8 are then supported on the straight intermediate portion 4, below the straight portions 2 and 3, 15 and at the same time are prevented from sliding off the holders by the bends 5 and 6, the garments, supported on the hangers, have a tendency, by their weight, to force the portion 4 downward so that the portion 2 will rest 20 upon, and frictionally engage, the portion 3, thereby virtually locking the portions 2 and 3 together and making the holder capable of sustaining a comparatively heavy load.

The holder may be of any length in order 25 to make it suitable for installation in various places and under varying conditions, but I prefer to construct the holder so as to accommodate thereon only a small number of hangers and thereby to make the holder especially 30 adapted to be attached transversely on a shelf, as indicated in Figure 1, in which the holder is shown as having five hangers thereon.

I claim as my invention:

1. A clothes-hanger holder comprising a 35 support, a ring depending from the support, a hook depending from the support and spaced from said ring; a rod comprising a straight end portion, a bent portion extending parallel with said straight end portion, 40 a rebent portion extending between said straight end and said bent portion and in parallelism therewith; said straight portion and rebent portion being spaced so as to allow the straight portion to be threaded thru the 45 eyes of a hanger and thru said ring, the end of said straight portion and the rebent portion to be removably suspended on said hook.

2. A clothes-hanger holder comprising a support, a ring depending from the support, 50 a hook depending from the support and spaced from said ring; a rod comprising a straight end portion, a bent portion extending parallel with said straight end portion, a rebent portion 55 extending between said

straight end and said bent portion and in 55 parallelism therewith; said straight portion and rebent portion being spaced so as to allow the straight portion to be threaded thru the eyes of a hanger and thru said ring, the end of said straight portion and the rebent portion to be 60 removably suspended on said hook, the free end of said rebent portion being curved so as to prevent the accidental removal of said rod from said ring and the accidental removal of said hangers. 65

3. A clothes-hanger holder comprising a support, a ring depending from the support, a hook depending from the support and spaced from said ring; a rod comprising a straight end portion, a bent portion extending 70 parallel with said straight end portion, a rebent portion extending between said straight end and said bent portion and in parallelism therewith; said straight portion and rebent portion being spaced so as to allow the 75 straight portion to be threaded thru the eyes of a hanger and thru said ring, the end of said straight portion and the rebent portion to be removably suspended so as to prevent the accidental removal of said rod from said ring and the accidental removal of said hangers, 80 said ring and said hook supporting said hanger rod in substantially a horizontal position.

4. A clothes-hanger holder comprising a 85 support, a ring depending from the support, a hook depending from the support and spaced from said ring; a rod comprising a straight end portion, a bent portion extending parallel 90 with said straight end portion, a rebent portion extending between said straight end and said bent portion and in parallelism therewith; said straight portion and rebent portion being spaced so as to allow the straight portion to be threaded thru the eyes of a 95 hanger and thru said ring, the end of said straight portion and the rebent portion to be removably suspended on said hook, the free end of said rebent portion being curved so as to prevent the accidental removal of said rod from said ring and the accidental removal of 100 said hangers; said ring and said hook supporting said hanger rod in substantially a horizontal position; a hinge securing means on one end of said support. 105

In testimony whereof I affix my signature,

ANNIE L. CHUBB.
